UNITED STATES PATENT OFFICE.

DANIEL W. MILLSAPS, OF WASHINGTON, DISTRICT OF COLUMBIA.

RAILROAD CROSSING.

Application filed December 3, 1924. Serial No. 753,672.

To all whom it may concern:

Be it known that I, DANIEL W. MILLSAPS, a citizen of the United States, residing at Washington, in the District of Columbia, 5 have invented new and useful Improvements in Railroad Crossings, of which the following is a specification.

This invention relates to railroad crossings.

10 The rails of the respective tracks are of course interrupted at their point of intersection, and the corners of the rails or crossing at this point are constantly battered by the wheels of the cars passing thereover, 15 which frequently necessitates the pointing of these corners at a considerable expense. Then again, the cars are subjected to undue jar as they pass over the crossing, and with resultant noise that is objectionable.

20 It is therefore the purpose of this invention to provide a plurality of blocks at each intersection, and arrange to fill the interrupted portions, and across which the treads of the wheels are adapted to pass, and thus 25 prevent battering of the corners as above stated, and to also materially reduce the noise incident to the passage of the cars over the crossing.

One of the chief characteristics of the 30 present invention resides in the manner of supporting each block, to allow the cars to pass over the crossing in either direction, each block being normally arranged vertically and yieldably held in this position by 35 means which allows the blocks to be moved by the flange of the wheel in either direction so as not to interfere with the travel of the cars as will be readily understood.

Another object of importance resides in 40 the crossing structure generally, which allows the blocks to be replaced when desired without removing the rails from their foundation, and allow this duty to be accomplished in a comparatively short time with a 45 minimum of expense.

The nature and advantages of the invention will be better understood when the following detailed description is read in connection with the accompanying drawings, 50 the invention residing in the construction, combination and arrangement of parts as claimed.

In the drawings forming part of this ap-

plication, like numerals of reference indicate similar parts in the several views, and 55 wherein:

Figure 1 is a top plan view showing how the blocks are arranged for the purpose specified.

Figure 2 is a sectional view taken on line 60 2-2 of Figure 1.

Figure 3 is a sectional view taken on line 65 3-3 of Figure 1.

Figure 4 is a fragmentary end elevation.

Figure 5 is a perspective view of one of 65 the tie plates.

Figure 6 is an end elevation of one of the rail sections forming part of the crossing structure.

Figure 7 is a perspective view of one of 70 the corner blocks.

Referring to the drawings in detail 10 represents a base plate which is arranged at each intersection, and of course embedded in the foundation beneath the interrupted portions of the rails as will be readily understood. Supported on this base plate are the corner pieces, each of which is of substantially L-shaped formation, in plan as clearly 75 illustrated in Figure 7. There are four of 80 these corner pieces 11 as shown in Figure 1, and each corner piece is held fixed relatively to the base plate 10 by suitable bolts 12 which are passed downwardly through the corner pieces and threaded or otherwise suitably secured to the base plate 10 as shown in Figure 3. The heads of the bolts are countersunk in depressions 13 in the tops of said corner pieces, the intersecting rails 14 and 15 of the trackway have their adjacent ends 90 supported upon the base plate 10 between each adjacent pair of corner pieces as shown in Figure 1, and consequently the corner pieces are suitably spaced apart to provide a groove or passage for the flange of each 95 car wheel. Interposed between the end of each rail, and the adjacent ends of the corner pieces is a rail section 16, and each section is preferably provided with a web 17 which is adapted to be received in the space 100 between the corner pieces 11, and bevelled to assist in forming the groove for the flange of the wheel as above stated. Each rail section 16 fills the space between the adjacent 105 end of the rail of the track and the corner pieces 11 for a purpose to be hereinafter de-

scribed in detail, namely to facilitate gaining access to the tread blocks 18 as the occasion may require.

Located within each flange receiving a groove defined by the space between the corner pieces 11 is one of the tread or filler blocks 18 and these blocks are of a size to lie flush with the surfaces of said cornerpieces, and utilized to provide a continuous tread 5 for the passage of the car wheels across the intersection. Each block is mounted for pivotal movement upon a pivot 19, which is carried by one corner piece of each pair of corner pieces, and adapted to be received by 10 an opening in the adjacent corner piece as will be readily understood. This pivot 19 is clearly shown in Figure 7, and is arranged above and parallel with a pair of pins 20 and 21, respectively, which also project laterally from the corner piece 11 supporting the pivot 19 and the opposite sides thereof. Pivotedly mounted on these pins 20 and 21 are spaced vertically disposed plates 22 and 23, respectively, which are normally arranged 15 in the manner shown in Figure 2, to maintain the adjacent filler block 18 in a vertical position. As shown in Figure 2, the plates 22 and 23 engage the opposite sides of the block 18 for the purpose just mentioned, the plates being maintained in this position through the instrumentality of coiled springs 24. There is one of these springs for each plate, the inner end of each spring being secured to a lug 25 depending 20 from the adjacent plate, while the outer end of the spring is secured in any suitable manner as at 26 to the base plate 10. By reason of this construction, it is manifest, that when the car is travelling in one direction, the flange of the wheel strikes one of the blocks 18 moving it to an out of the way position upon its pivot 19 and against the tension of one of the springs 24, and after 25 the car has passed over the crossing the particular block so effected is automatically returned to its normal position by means of one of said springs. The other block remains in its normal position and provides a support for the wheels of the car, the treads of the wheels engaging the last 30 mentioned blocks, so that the car can pass over the crossing smoothly, and eliminate the jar and noise above referred to. Also projecting from the corner piece 11 supporting the pivot 19 are pins 27, there being one of these pins for each of the pivoted plates 22 and 23, respectively, the pins being arranged to limit the movement of each plate when it is returned to its normal position under the influence of the spring 24. In addition to using the bolts 12 for holding the corner pieces 11 fixed relatively, I also employ plates 28 such as shown in Figure 5, each plate having a plurality of squared 35 openings 29 to receive lugs 30 which rise

from the base plate 10, when these parts are operatively associated. This construction is shown in Figures 1 and 3, wherein it will be noted that one of the plates 28 is used in connection with each corner piece 11, with one corner of each plate 28 snugly fitted in the angle between the branches of the adjacent corner piece. The entire structure is very strong and rigid.

Now, should it be necessary to replace any 40 or all of the blocks 18, this can be conveniently and quickly accomplished without disturbing the rails of the trackway. For this purpose it is only necessary to remove the rail sections 16 above referred to together with their webs 17 as each of these sections can be lifted upwardly from the surfaces between the corner pieces 11. When the said rail sections are removed, ample space is provided between the adjacent ends 45 of the rails of the track and the ends of the corner pieces to allow the corner pieces to be slid upon the base 10 sufficient distance to separate them from the adjacent corner pieces, with which they are associated by 50 means of pivots 19 and the various pins above described. Of course to slide any of the corner pieces 11 of the base plate 10 for this purpose, it is necessary to remove the bolts 12, and also separate the plates 28 55 from the base plate 10.

While it is believed that from the foregoing description, the nature and advantages of the invention will be readily apparent, I desire to have it understood that I do not 60 limit myself to what is herein shown and described, and that such changes may be resorted to when desired as fall within the scope of what is claimed.

Having thus described the invention, I 65 claim:

1. In a railroad crossing, cross rails having interrupted portions therein adjacent their points of intersection, blocks filling said interrupted portions and mounted for pivotal movement in either direction, and yieldably mounted plates arranged at the opposite sides of each block for normally holding the latter in a vertical position for the purpose specified.

2. In a railroad crossing, crossing rails having interrupted portions adjacent their points of intersection, blocks filling said interrupted portions and mounted for pivotal movement in either direction, a pair of parallel plates arranged at opposite sides of each block in contacting engagement therewith, said plates being capable of pivotal movement in either direction, and yieldable means connected with each plate to hold the latter and said blocks normally vertical for the purpose specified.

3. In a railroad crossing, cross rails having interrupted portions therein adjacent their points of intersection, blocks filling

5 said interrupted portions and mounted for pivotal movement in either direction, means for normally holding each block in a vertical position, said means including a pair of spaced pivoted plates arranged at the opposite sides of each block and in contacting engagement therewith, and a yieldable element terminally connected with each plate, and a stop arranged in the path of 10 movement of each plate, to limit the movement of the latter under the tension of said yieldable element.

15 4. A railroad crossing comprising a base plate, angular corner pieces supported on said plate and spaced apart to receive the adjacent ends of the rails of the track at their points of intersection, blocks pivoted between the adjacent pairs of corner pieces for filling the interrupted portions of the 20 rails and mounted for pivotal movement in either direction, and yieldably mounted plates arranged at the opposite sides of each block when normally holding the latter in a vertical position for the purpose specified.

25 5. In a railroad crossing, a base plate, angular corner pieces supported thereon and spaced apart, the adjacent ends of said rails

30 at their point of intersection being supported on said base plate, a rail section interposed between the adjacent end of each rail and the adjacent corner pieces and supported on said base plate, a web forming part of the rail section and positioned between the adjacent corner pieces, and capable of being lifted therefrom to provide a space between 35 the corner pieces and the adjacent rail to allow the corner pieces to be shifted upon the base for separation from each other, a pivot projecting from one corner piece of each pair and received by an opening in the other 40 corner piece, a block mounted on each pivot for filling the interrupted portions at the crossing for the purpose specified, each block being mounted for pivotal movement in either direction, and yieldably mounted 45 plates arranged at the opposite sides of each block and utilized to normally hold each block in a true vertical position, and a stop arranged in the path of movement of said plates to limit the movements of the latter 50 in one direction.

In testimony whereof I affix my signature.

DANIEL W. MILLSAPS.
